UNITED STATES PATENT OFFICE.

JOHN J. KENNELLY, OF NEW YORK, N. Y.

FARE-REGISTER.

SPECIFICATION forming part of Letters Patent No. 616,932, dated January 3, 1899.

Application filed June 21, 1897. Serial No. 641,728. (No model.)

To all whom it may concern:

Be it known that I, JOHN J. KENNELLY, a citizen of the United States, residing at New York, in the county of New York and State 5 of New York, have invented certain new and useful Improvements in Fare-Registers; and I do declare the following to be a full, clear, and exact description of the invention, such as will enable others skilled in the art to which 10 it appertains to make and use the same, reference being had to the accompanying drawings, and to the letters and figures of reference marked thereon, which form a part of this specification.

15 My invention relates to that class of registers designed for use on passenger-vehicles to register the number of passengers or the number of fares received.

More specifically it relates to that variety 20 of registers having a resettable registering mechanism for registering the passengers or fares of each trip, and a permanent or total registering mechanism for registering the aggregate number of passengers or fares of suc- 25 cessive trips.

My improvements comprehend means for disconnecting the trip-register from the actuating mechanism, means for resetting the trip-register to zero, means for maintaining a 30 broken connection until the trip-register has been fully reset, means for automatically re-establishing connection between the trip-regis- 35 ter and the driving mechanism on the completion of the resetting operation, and details of construction and combinations of parts, as specifically defined in the appended claims.

In the accompanying drawings, Figure 1 represents a face view of the base-plate with the actuating or driving mechanism mounted 40 thereon; Fig. 2, a section on the line $x-x$ in Fig. 6; Fig. 3, a front view of the register with the face-plate removed; Fig. 4, a rear view of bridge with the registering mechanism mounted thereon; Fig. 5, a face view of 45 the register complete; Fig. 6, a side view, from the left-hand side, of the bridge and the mechanism mounted thereon; Fig. 7, a broken section on the line $y-y$ in Fig. 3. Fig. 7^a is a transverse section on the line $z-z$ in Fig. 1; 50 Fig. 8, a view showing the means for locking the operating-lever when the trip-register is disconnected from the driving mechanism;

Fig. 9, a broken sectional view showing the means for resetting the trip-register; Fig. 10, a side view, partly in section, showing the 55 means for disconnecting the trip - register and the means for operating the direction-indicator. Figs. 11, 12, 13, 14, and 15 are detail views which will be fully understood from the following description. Fig. 16 is a broken 60 section on the line $v-v$ of Fig. 15.

Referring to the drawings, A designates the rear or base plate of the machine. It is of circular form and has at its center a forwardly-projecting hollow boss 2, on which is 65 fulcrumed an elbow-lever 3, having at the end of one of its arms a backwardly-projecting pin 4, which extends through a slot 5 in the base-plate A for the attachment thereto of the usual or any suitable operating de- 70 vices. The other arm carries a pawl 6, which is arranged to engage the teeth of a ten-toothed ratchet-wheel 7 to advance the latter one step or through the angular distance of one tooth at each vibration of the lever, the 75 movements of the wheel being effected at the back stroke under the influence of a spring 8. A stop 9 limits the movement of the lever.

10 designates the alarm - bell, and 11 the bell-hammer, which is mounted on a stud 12 80 and is thrown toward the bell by a spring 13. The shank of the hammer has a cam-tooth 14, which is acted on by the teeth of the ratchet-wheel 7 to retract the hammer, the arrangement being such that the hammer is 85 operated by each tooth and such that it is released to strike the bell at the completion of each forward movement of the ratchet-wheel.

15 designates a gear-wheel provided with a hub 15^a, which is journaled in the hollow boss 2. This wheel meshes with and is driven by a pinion 16, formed on or rigidly attached to the ratchet-wheel 7. Preferably the pinion is formed with ten teeth and the wheel 15 with 95 one hundred.

In front of the base-plate A and the devices mounted thereon, as above explained, is a second plate B, which I denominate the "bridge." This plate is mounted on the ends of forwardly-projecting studs $a a' a'' a'''$, and it forms the support for the registering mechanism hereinafter described.

In front of the bridge B is a toothed wheel

17, which is rigidly connected with the gear 15, and in front of the wheel 17 is a gear-wheel 18, provided with a rearwardly-extending shaft 18^a, that projects through the hollow hub of gear 15 to the rear of the machine, where it is provided with a collar 19, the length of said shaft and the arrangement of the collar being such as to permit limited forward movement of the wheel 18 in opposition to a spring 20, which surrounds the shaft 18^a and has bearings against the collar 19 and a shoulder in the hub 15^a.

On the rear face of the wheel 18 is formed one or more lugs or teeth 21, which when the wheel is in its normal position, as shown in full lines in Fig. 7, enter between and engage the teeth of wheel 17, whereby independent rotation of wheel 18 is prevented so long as said engagement is maintained; but when the connection is broken by moving the wheel 18 forward, as indicated by broken lines in Fig. 7, the wheel 18 may turn independently. The purpose of this construction and arrangement will be explained presently.

22 23 are the two register-wheels (units and tens, respectively) which constitute the "trip-register" for registering the passengers or fares of each trip. They are resettable and are intended to be reset at the end of each trip or at predetermined points on the line. They are mounted on studs or pintles 22^a and 23^a, which project forward from the bridge B at opposite sides of the center of the machine.

35 On the under or rear side of the units-wheel 22 and connected therewith is a pinion 24, which meshes with and is driven by the gear-wheel 18, to which motion is imparted from the lever 3 through the ratchet-wheel 7 and its pinion 16, as above explained, so that at each operation of the lever the wheel is advanced one step to expose the next higher numeral thereon through a sight-opening c in the face-plate C.

45 In order to "carry" or transfer the tens from the units-wheel 22 to the tens-wheel 23, the latter is advanced one step at the completion of each full rotation of the units-wheel or at the return of the units-wheel to the zero position. This is effected as follows: A wheel 25, having a single tooth 25^a, is mounted on a stud or pintle 26. On the under side of this wheel and fast thereon is a pinion 27 of the same size as the pinion 24 and which is also in mesh with and driven by the gear 18, so that at each operation the wheels 22 and 25 are rotated through the same angular distance and so that they complete their rotations together. The pinions 17 and 24 are of sufficient length to remain in mesh with the gear 18 when the latter is moved from one of its positions to the other. The wheel 25 co-operates in the usual manner with a scalloped wheel 28, fast on the under or rear side of the tens-register wheel 23 to advance the latter one step at the completion of each rotation of the wheel 25 and to hold it in

fixed position during the intervals between its step-by-step movements. This part of the mechanism involves no part of my invention, and therefore requires no further description.

The machine having been operated to register the passengers or fares of a trip, it is reset to zero in the following manner and by the following means:

29 designates a lever fulcrumed in lugs or ears 30 31, formed on the bridge B, as shown in Fig. 2. This lever is formed with an eye or opening 32 for the reception of a hub or boss 33, formed on the front of the gear-wheel 18, and it is coupled to said gear by means of a plate or washer 34, secured upon said hub or boss 33 and overlapping the lever. At its lower end the lever 29 is provided with a push-pin 35, which projects to the back of the machine through a notch or opening in the bridge B, whereby it is adapted to be swung forward to draw the gear-wheel 18 forward and break the connection between the wheels 17 18. The latter is then free to rotate independently of the wheels 17 15; but it is rotatable only in a backward direction, being then out of engagement with a pawl 36, which at other times prevents it from rotating backward. This backward rotation of course turns the register-wheels 22 23 back also until both reach the zero position, at which time a stop-lug 37 on the wheel 18 strikes an arm 38, which overlies said wheel at a distance therefrom to permit it to be moved forward to break connection with wheel 17, as already explained.

To prevent forward rotation of wheel 18 while it is disconnected from wheel 17, I provide a pawl 39, which in the normal position of the wheel stands above or in front of the same; but when the wheel is moved forward preparatory to resetting it comes into the plane of the pawl and the latter then prevents forward rotation. In its normal position the wheel 18 is held against backward rotation by a pawl 40; but when it is moved forward preparatory to resetting it moves away from this pawl and is then free to turn backward. It will thus be understood that the two pawls 39 40, which point toward each other, act alternately, the pawl 39 being in action when 40 is out of action, and vice versa.

When the lever 29 is thrown forward to disconnect the wheels 17 18 preparatory to resetting, it is desirable that the machine shall be locked against all operation except that of resetting the trip-register to zero and that it shall remain in such locked and inoperative condition until it has been fully reset. For this purpose I provide, first, a means for locking the lever 3 against operation while the connection between the wheels 17 18 remains broken, and, second, a means for preventing the lever 29 from returning to normal position after it has been thrown out to separate the wheels 17 18 until the resetting has been fully accomplished—that is, until the wheel

18 has been turned entirely back to the starting-point.

First as to the means for locking the lever 3 against operation: On a lug or standard 3 41, formed on the base-plate A, is pivoted a dog 42, to which is applied a spring 43 to throw the inner end into the path of the lever 3. The outer end of this dog 42 is bent forward and projects through an opening in the bridge 10 B into the range of movement of the lever 29, the arrangement being such that when the lever 29 is in its normal position and the register in operative condition the lever 29 presses down the outer end of the dog 42 and 15 raises the inner end thereof above the lever 3, the latter being then free to be operated; but when the lever 29 is thrown out preparatory to resetting the register it releases the dog 42 and permits its spring 43 to throw its inner 20 end into the path of lever 3 to lock the latter against operation.

The means for preventing the return of lever 29 to normal position after it has been thrown out to break the operative connection, 25 as explained, comprehends a lever 44, mounted on a stud 45, projecting out from the bridge B. This lever is provided with a spring 46, applied to throw the outer end toward the lever 29, and as soon as the latter is operated 30 the lever 44 turns thereunder and prevents a return movement. At its opposite end, which projects somewhat over the gear 18, the lever 44 carries a pivoted dog 47, the free end of which is bent toward the gear 18, and in 35 the normal or operative position of the latter stands in close proximity thereto. When the gear 18 is moved forward by operating the lever 29, it presses against the dog 47 and turns it on its pivot against the force of a 40 spring 48, applied thereto to press it back. In the gear 18 is formed an opening 49, located with respect to the dog 47 and the zero position of the wheel so that the dog will drop into said opening just before the wheel 45 reaches the limit of its movement in resetting the register to zero and so that the final movement will turn the lever 44 and withdraw it from under the lever 29, leaving the latter free to return to normal position under the 50 combined action of the spring 20 and a spring 50, applied to said lever above its fulcrum.

The trip-register as thus far described has a registering capacity of "99." This capacity is increased by means of a swinging plate 51, 55 which is fulcrumed at 52^a and which overlies the tens-register wheel 23. This plate has on its face the digit "1," which in one position of the plate stands within the sight-opening c in close proximity to the line of numerals 60 on the tens-wheel 23 and in the other position stands under and is hidden by the face-plate C. This plate then registers "100," and it is brought into action at the tenth forward movement of the tens-register wheel 23—that 65 is, at the completion of its first rotation, or during the movement from the "9" position to the zero or "0" position.

The construction and operation are as follows: The plate 51 is connected with a sleeve or hub 52, which is loosely mounted on a stud 70 or pintle 52^a, projecting forward from the bridge B, and a spring 54, applied thereto, has a constant tendency to throw it toward the left away from the sight-opening c. The sleeve or hub 52 has two arms 55 56, the first 75 of which stands toward the lever 29 and the second toward the axis of the register-wheel 23. On the under or rear side of the register-wheel 23 is an arm 57, which on the completion of the first rotation of said register-wheel—that is to say, after it reaches the highest or "9" position—and during its movement from said highest position to the lowest or zero position, strikes a lever 58, fulcrumed on a pintle 59, and turns said lever toward the 80 left. The lever 58 is coupled with the arm 56, and when operated, as stated, turns said arm toward the right, carrying the plate 51 (or the numeral thereon) under the sight-opening c. When this occurs, a spring-pressed 85 latch 60, pivoted on the side of the lever 29, falls in behind the arm 55 and holds the latter, preventing a return movement of plate 51 under the action of spring 54.

As already explained, the first step in the 90 operation of resetting the register to zero is the throwing forward of lever 29 to break the connection between the wheels 17 18, and when this is done the latch 60, whose movement is limited by a stop-pin 61, is carried, 95 with the lever 29, out of engagement with the arm 55, permitting the latter and the plate 51 to return to normal position (indicated by full lines in Fig. 3) under the influence of spring 54. The end of arm 55 then passes 100 under the latch 60, so that when the lever 29 returns to normal position after the register has been reset the said latch rests on said 105 arm ready to drop in and engage the same, when the plate is again thrown over the right. 110 Means for resetting to zero are provided as follows:

Connected with the pinion 24 and through the latter with the units-register wheel 22 is a bevel-gear 62, which meshes with a similar 115 gear 63, mounted on the inner end of a short shaft 64, that is mounted in a bearing 65 on the bridge B. (See Figs. 2 and 4.) The outer end of this shaft 64 is provided with a finger-knob or with a plate 66, whereby it is adapted 120 to be turned by hand. The pinion 24 is of sufficient length to extend beyond the range of movement of the gear 18, so that these always remain in mesh and so that when the connection between the wheels 17 and 18 is 125 broken the pinion 24, operated through the bevel-gears 62 63, serves to return the gear 18 to the starting-point and through it to reset the register-wheels 22 23 to zero.

The units-register wheel has connected with 130 it a ratchet-wheel 67, whose teeth, ten in number, point in the direction of rotation, and which has for its purpose to prevent over-rotation of the register-wheels 22 23, the opera-

tion being as follows: The horizontal arm of the lever 3 carries a post or standard 68, on the end of which is mounted a pawl 69, which when the lever stands in normal position, as 5 in Fig. 1, engages said ratchet-wheel and prevents forward rotation. When the lever is operated—that is, when it is drawn toward the left—the pawl 69 moves away from the ratchet-wheel, leaving the latter free to rotate. It, however, stands still until the lever 10 3 begins its return movement under the influence of spring 8, whereby the ratchet-wheel 7 is moved forward one step and the register-wheels 22 23 are advanced through the train 15 of gearing 16 15 18 24 25 27 28, as already fully explained. While this movement is in progress, the pawl 69 is moving toward the ratchet-wheel 67, and before the latter passes through the angular distance of one tooth the 20 pawl is in position to catch the advancing tooth and arrest the whole movement on the completion of one-tenth of a rotation of the register-wheel 22. The pawl 69 is spring-pressed, but its forward movement is limited 25 by a pin 68^a, which projects into an opening therein from the standard 68, so that it is always in operative position.

70 designates the direction-indicator, comprising a parallelepiped of sufficient length 30 to bear on its side faces the appropriate legends as "Up," "Down," "In," "Out," &c., to indicate to the passengers the direction in which the car is traveling. This indicator is mounted on an axis 71, journaled in lugs or 35 ears 30 30^a. The projecting journal at one end—that toward the lever 29—has mounted on it a four-toothed ratchet-wheel 72, which is operated on a by pawl 73, carried by a swinging arm 74, pivoted on the ear 30. The arm 40 74 has a pin 75^a, which is engaged by the upper end of the lever 29, the arrangement being such that when the lower end of lever 29 is thrown out preparatory to resetting the register the arm 74 is swung back and the 45 pawl 73 carried into engagement with the next succeeding tooth of the ratchet-wheel 72. Then when the lever 29 is permitted to return to normal position after the resetting has been completed the arm 74 is swung forward 50 and the ratchet-wheel 72 and indicator 70 turned a quarter rotation to bring the next face of the indicator into view through the sight-opening c' in the face-plate C. A pawl or dog 75, pivoted on the ear 30, serves to prevent back rotation of the indicator while the 55 pawl 73 is moving from one tooth of the ratchet-wheel to the next.

This machine, like others of its class, is provided with a permanent or total register 60 to register the aggregate number of fares of successive trips. This permanent register forms no part of this invention and need not, therefore, be described with any particularity. e f g h are four register-wheels operating together, as usual. The wheel h has connected with it a bevel-gear i, which meshes with a similar gear j. The gear j has con-

nected with it a pinion (not shown) which is driven by a gear k, mounted on a bracket l, back of the bridge, said gear being in turn 70 driven by the main gear 15. This permanent register is always in gear with the driving mechanism; but the locking of the lever 3 against operation when the trip-register is out of action and while it is being reset, as 75 fully explained, renders it inoperative except when the trip-register is in operative condition.

This invention is designed as an improvement on that shown and described in United States Letters Patent No. 547,981, issued October 15, 1895, to John B. Benton, the objects being simplicity of construction, reduction in the number of parts, and reduction in the cost of manufacture. 80

Having now described my invention, I claim—

1. In a resettable trip-register the combination with the register-wheels, of a gear for rotating the same, a driven gear and means 90 for rotating the same step by step, a toothed wheel rigidly connected with said driven wheel adjacent to the register-operating gear, and projections on the latter adapted to engage separably with said toothed wheel. 95

2. In a resettable trip-register the combination with the register-wheels, of a gear for rotating the same, said gear being movable in the direction of its axis, a driven gear and means for rotating the same step by step, a 100 toothed wheel rigidly connected with said driven gear adjacent to the said gear for operating the register-wheels, the latter being provided with projections adapted to engage with, and to be disengaged from, said toothed 105 wheel.

3. In a resettable trip-register, the combination with the register-wheels, of a gear operating therewith to rotate the same, and movable in the direction of its axis, a driven gear 110 and means for rotating the same step by step, a toothed wheel connected with said driven wheel adjacent to the said gear for operating the register-wheels, projections on said register-operating gear adapted to engage with, 115 and to be disengaged from, said toothed wheel, a spring operating to maintain connection between said gear and wheel, and means for moving said gear to break said connection preparatory to resetting the register-wheels. 120

4. In a trip-register the combination with the register-wheels, of a reciprocating actuator or driving mechanism and intermediate gearing for rotating the register-wheels, a separable connection in said intermediate 125 gearing, a lever for breaking connection, and a dog under the control of said lever for engaging with and locking the actuator when the connection is broken and unlocking it when the connection is restored.

5. In a fare-register the combination of a register-wheel having thereon numerals of a given order, a face-plate in front of said register-wheel having a sight-opening through 130

which said numerals are displayed in succession, a movable plate having thereon a digit or numeral of higher order, means for holding said plate normally away from said opening, and devices operated by the register-wheel at the completion of a rotation thereof to move said plate into position to expose the digit thereon through the sight-opening in connection with the zero character on the register-wheel.

6. In a fare-register the combination with the register-wheels, of an actuating mechanism, a gear between the actuating mechanism and the register-wheels for operating the latter, said gear being movable in a direction at right angles to the plane of rotation and having separable connection with the actuating mechanism, a manually-operated lever coupled with said gear for moving the same to break said connection, and a pivoted spring-pressed lever arranged and adapted to pass under, or behind, said manually-operated lever to prevent return thereof to normal position.

7. In a fare-register the combination with the register-wheels, of an actuating mechanism, a gear between the actuating mechanism and the register-wheels for operating the latter, said gear being movable in a direction at right angles to the plane of rotation and capable, when moved out of its normal position, of being rotated backward to reset the register-wheels, a manually-operated lever for moving said gear out of its normal position, a spring-actuated lever arranged and adapted to prevent the return of said manually-operated lever to normal position, and a pivoted dog on said pivoted lever, and means whereby the gear, during its backward rotation, is adapted to engage said dog and operate said pivoted lever to release said manually-operated lever, the arrangement being such that the gear is permitted to return to normal position at the completion of the resetting operation.

8. In a fare-register the combination with the register-wheels, of the gear 18 for rotating the same, said gear being movable, as described, and having separable connection with the driving mechanism, the lever 29 for moving said gear, and the pivoted spring-actuated lever 44 provided with the dog 47, said devices operating together in the manner and for the purposes described.

9. The combination with the resettable register, of a gear for operating the same, said gear being movable in the direction of its axis and having a separable connection with the driving mechanism, a manually-operated lever for moving said gear to break the connection, a spring-actuated lever lying in the plane of said manually-operated lever when the latter is in its normal position and adapted to pass thereunder, to prevent return movement, when the connection is broken, and means for automatically operating said spring-actuated lever to release the manually-operated lever at the completion of the resetting operation.

10. In a resettable register the combination with the register-wheels, of a gear for operating the same, said gear having separable connection with a driving mechanism and being capable of movement in the direction of its axis to break connection, and of rotating backward, to reset the register, when the connection is broken, means for limiting backward rotation, a manually-operated lever for moving said gear to break connection, a spring-pressed lever lying in the plane of said manually-operated lever and adapted to pass thereunder to prevent return movement when the connection is broken, and means on said wheel, for operating said spring-pressed lever to release the manually-operated lever at the completion of the resetting operation.

11. In a fare-register the combination with the resettable trip-register, of the gear 18 for operating the same, said gear having a separable connection with a driving mechanism and being capable, when said connection is broken, of being rotated backward to reset the register, the lever 29 coupled with the gear 18 for breaking connection between the latter and the driving mechanism, the lever 44 adapted to turn under the lever 29 and prevent return movement of the latter when the connection is broken, the dog 47 on the end of the lever 44, said dog being adapted to be engaged by the wheel and operated to release the lever 29 at the completion of the resetting operation.

In testimony whereof I affix my signature in presence of two witnesses.

JOHN J. KENNELLY.
